UNITED STATES PATENT OFFICE

SAMUEL M. RIKER, OF CHESTER, NEW JERSEY

SHOE BUCKLE

Application filed August 14, 1931. Serial No. 556,966.

This invention relates to an improved construction of buckle which is especially adapted for use in connection with the fastening straps of shoes or slippers.

This invention has for its principal object to provide a buckle body having comparatively widely separated strap-receiving loops, with one of which is cooperatively arranged a pivoted buckle tongue, an integrally formed attachment and spacing bar being provided in longitudinal extension between said strap-receiving loops, said bar preferably being of laterally tapering conformation and having transversely opposite marginal notches or openings to form means in connection with which may be sewn stitches for attaching the buckle to a shoe or slipper side, whereby the buckle is securely held against displacement from its normal attached position on said shoe or slipper side, and yet is free for more or less easy tilting movement relative to the point of attachment so as to render the same easily manipulated when coupling a free strap end thereto and therewith; a further advantage of the novel attachment bar formation being that it may be made very narrow as compared with the width of the strap-receiving loops, so as to be entirely concealed when the free strap end is coupled with the buckle, thereby enhancing the neat and trim appearance of the latter when performing its fastening functions.

Illustrative embodiments of this invention are shown in the accompanying drawings, in which:—

Fig. 1 is a face view of the novel buckle of this invention with a strap member operatively coupled therewith; Fig. 2 is an edge view of the same; Fig. 3 is a face view with the strap member disconnected therefrom, this view showing the novel attachment and spacing bar of the buckle and the sewn stitches as operatively related thereto for securing the buckle to a shoe or slipper side; Fig. 4 is a view similar to that of Fig. 3, but showing the sewn stitches in horizontal section, to more clearly illustrate one arrangement of fastening stitches relative to the attachment bar; Fig. 5 is a transverse sectional view, taken on line 5—5 of Fig. 3, but drawn

on an enlarged scale; and Fig. 6 is a view similar to that of Fig. 3, but showing a modified arrangement of fastening stitches relative to the attachment bar.

Similar characters of reference are employed in the above described views, to indicate corresponding parts.

The novel buckle of this invention, in one form, comprises the closed strap-receiving loops 6 and 7, which may be of any selected ornamental shape and configuration, the same being arranged in separated longitudinally spaced apart relation. Integrally connected with the opposed sides of said loops 6 and 7, so as to extend longitudinally therebetween, is a combined attachment and spacing bar 8 of laterally tapering shape, having, adjacent to the juncture of its broad end with the loop 6, a perforation 9 contiguous to said loop 6, whereby the pivoting knuckle 10 of a buckle tongue 11 may be engaged with the inner side of said loop 6, so that the tongue may cross the loop opening to permit engagement of its free end with the outer side of said loop 6; the narrow end of said bar joining the inner side of said loop 7.

The buckle is adapted to be attached by sewing to a side portion or wing 12 of a shoe or slipper. One method of so attaching the buckle is shown in Figs. 1 to 5 inclusive, wherein the attachment bar 8 is provided, intermediate its ends with transversely opposite indented marginal notches 13, forming therebetween a neck 14. The sewn fastening stitches 15 are sewn through the shoe or slipper side portion or wing 12 to pass over or through the marginal notches 13 and across the neck 14, thus not only securing the buckle in place, but, by reason of the seating of the stitches 15 within the notches 13, also preventing any longitudinal shifting or displacement of the buckle relative to the desired position of attachment, while nevertheless leaving the buckle comparatively free for such tilting movement relative to the point of attachment, as will render easy the manipulation thereof when coupling a strap-member 16 therewith. Said strap-member 16 is suitably secured to and extends from the opposite side portion of a shoe or slipper.

Referring to Fig. 6 of the drawings, there is shown a modified arrangement of fastening stitch engageable means in connection with the attachment bar 8. In this modified arrangement, external arcuate ears 17 are integrally formed to extend about the notches 13, whereby stitching 18 may be sewn over the opposite ears 17 and through the thus enclosed notches 13, to securely hold the buckle in anchored relation to the shoe or slipper side or wing 12, and yet free to tilt or rock about the point of attachment thus provided.

When applying the strap-member 16 in operative coupled relation to the buckle, the former is passed beneath the outer side of the loop 6 upwardly through the interior thereof, whereupon the buckle tongue 11 may be engaged through a selected perforation 19 of the strap-member in the familiar manner. After the strap-member is thus engaged, the free end thereof is passed over the attachment bar 8 and then through the opening of loop 7 to pass beneath and beyond the outer side of the latter. When the strap-member is thus engaged with the buckle, it will cover over and entirely conceal the attachment bar 8 and associated stitching (see Fig. 1), thus attaining a buckle and strap relation of extremely neat and attractive appearance.

Having thus described my invention, I claim:

1. In a buckle, a body comprising a pair of longitudinally spaced strap-receiving loops integrally interconnected by a relatively narrow combined spacing and attachment bar extending centrally between said loops; a buckle tongue pivoted to and extending across one of said loops, and said attachment bar having transversely opposite marginal thread engageable portions intermediate its ends whereby said buckle body is retained against longitudinal displacement relative to fastening stitches applied thereto while yet being free to tilt relative to its point of attachment.

2. In a buckle, a body comprising a pair of longitudinally spaced strap-receiving loops, a longitudinal bar integrally connected with and extending between said loops, said bar being laterally tapered from one loop to the other and having a perforation at its broader end contiguous to the adjacent loop, a buckle tongue having a pivoting knuckle engaged through said perforation and around the inner side of the latter loop to extend across the same, and said bar having transversely opposite marginal thread engageable portions adjacent its narrower end.

3. In a buckle, a body comprising a pair of longitudinally spaced closed strap-receiving loops, a relatively narrow combined loop spacing and attachment bar integrally connected with and extending centrally between

said loops, said attachment bar having thread engageable seats intermediate its ends to retain the buckle when sewn in place against shifting or longitudinal displacement therefrom, and a buckle tongue pivoted to and extending across one of said loops.

In testimony, that I claim the invention set forth above I have hereunto set my hand this 8th day of August 1931.

SAMUEL M. RIKER.
